UNITED STATES PATENT OFFICE.

EVELYN ASHTON FLETCHER, OF TORONTO, CANADA.

DESIGN FOR A MUSIC-TIME-DIVISION BLOCK SET.

SPECIFICATION forming part of Design No. 28,029, dated December 14, 1897.

Application filed July 1, 1897. Serial No. 643,156. Term of patent 7 years.

To all whom it may concern:

Be it known that I, EVELYN ASHTON FLETCHER, a subject of the Queen of Great Britain, residing at the city of Toronto, in the county of York, in the Province of Ontario, Canada, have invented and produced a new and original Design for a Music-Time-Division Block Set, of which the following is a specification, reference being had to the accompanying drawing, forming part thereof.

My invention relates to a design for a music-time-division block set, of which the following is a specification.

The drawing represents a perspective view showing the design of the block set.

The design comprises a plurality of flat strips or blocks arranged parallel edge to edge. When so arranged, beginning with the block A, each strip is made one-half of the length of the preceding strips.

What I claim is—

The design for a music-time-division block set substantially as herein shown and described.

EVELYN ASHTON FLETCHER.
